(57) **CLAIM**

The ornamental design for a display case with detachably coupled panel access, as shown and described.

DESCRIPTION

FIG. 1 is a top, front perspective view of the display case with detachably coupled panel access;

FIG. 2 is a front elevation view thereof, a rear elevation view thereof being identical to the front elevation view shown; FIG. 3 is a left side elevation view thereof, a right side elevation view thereof being identical to the left side elevation view shown;

FIG. 4 is a top plan view thereof;

FIG. 5 is a bottom plan view thereof;

FIG. 6 is a top, front perspective, exploded view thereof, with the top panel shown detached from the upper edges of the side walls;

FIG. 7 is a bottom, front perspective, exploded view thereof, with the top panel shown detached from the upper edges of the side walls; and,

FIG. 8 is a front sectional view thereof, taken along line 8 shown in FIG. 4.

The broken lines in the drawings illustrate portions of the article that form no part of the claimed design.

1 Claim, 7 Drawing Sheets
